FIG. 1

FIG. 2

FIG. 3

FIG. 4

FIG. 5

FIG. 1 is a bottom plan view of a prismatic light panel showing our new design;

FIG. 2 is a top plan view thereof;

FIG. 3 is a longitudinal side elevational view thereof;

FIG. 4 is an enlarged cross-sectional view taken on line 4-4 of FIG. 2; and

FIG. 5 is an enlarged cross-sectional view of a second embodiment of our design, being taken on a plane identical to line 4-4 in FIG. 2, it being understood that the second embodiment has substantially the same appearance in top and bottom plan views as the first embodiment.

The prismatic light panel is understood to have indeterminate length and width.

We claim:

The ornamental design for a prismatic light panel, substantially as shown and described.
